Primary Examiner — Garth Rademaker*Assistant Examiner* — Joseph Hays(57) **CLAIM**

The ornamental design for a UAV ground control station, as shown and described.

DESCRIPTION

FIG. 1 is a front elevational view of a UAV ground control station embodying our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan thereof;

FIG. 7 is a top front perspective view thereof; and,

FIG. 8 is a top rear perspective view thereof.
